US0D1111198S

(12) **United States Design Patent** (10) Patent No.: **US D1,111,198 S**
(45) Date of Patent: ** Feb. 3, 2026

(54) **SLAB**

(71) Applicant: **POKARNA ENGINEERED STONE LIMITED**, Secunderabad (IN)

(72) Inventors: **Vedant Kakarania**, Secunderabad (IN); **V. Nikhil Sainath Reddy**, Secunderabad (IN); **Sanjay Sundar Kumar**, Secunderabad (IN); **Sujay Dinkar Borle**, Secunderabad (IN); **Ravi Prakash VSVSB**, Secunderabad (IN); **Koppisetti Sai Gowtham**, Secunderabad (IN); **Syed Mohd Faran**, Secunderabad (IN); **M. Mohana Krishnan**, Secunderabad (IN)

(73) Assignee: **POKARNA ENGINEERED STONE LIMITED**, Secunderabad (IN)

(**) Term: **15 Years**

(21) Appl. No.: **29/949,245**

(22) Filed: **Jun. 26, 2024**

(30) **Foreign Application Priority Data**

Apr. 18, 2024 (IN) 414072-001

(51) **LOC (15) Cl.** **25-01**

(52) **U.S. Cl.**

USPC **D25/151**; D25/138

(58) **Field of Classification Search**

USPC D25/138-140, 163, 149, 143-145, 147, D25/157-160; D6/582; D5/44, 53, 60
CPC . E04F 15/02; E04F 15/10; E04F 15/08; E04F 21/0092; E04F 13/0871
